STRIP CUTTING MACHINE

Philip H. Unsinger, Fremont, Ohio, assignor to
 Unsinger A P Corporation, Fremont, Ohio, a
 corporation of Ohio

Application July 5, 1947, Serial No. 140,127

Term of patent 7 years

(Cl. D55—1)

To all whom it may concern:

Be it known that I, Philip H. Unsinger, a citizen of the United States, residing at Fremont, county of Sandusky, and State of Ohio, have invented a new, original, and ornamental Design for a Strip Cutting Machine, of which the following is a specification, reference being had to the accompanying drawings, forming part thereof.

In the drawings:

Fig. 1 is a perspective view of a strip cutting machine, showing my new design;

Fig. 2 is a top plan view;

Fig. 3 is a front elevation view;

Fig. 4 is a rear elevation view; and

Fig. 5 is an end elevational view thereof.

I claim:

The ornamental design for a strip cutting machine, substantially as shown.

PHILIP H. UNSINGER.
